Application January 9, 1945, Serial No. 571,979

10 Claims. (Cl. 153—46)

1

This invention relates to bending machines of the character used in the fabrication of metal bodies and parts by bending and aims to provide an improved machine of this kind with which such bending operations can be carried out in a rapid and satisfactory manner, without buckling or wrinkling of the work material, and which will be readily adaptable for operating on various kinds of work material such as pipes, tubes, sheets, or the like.

Another object of this invention is to provide an improved bending machine of the character mentioned, which is of a more simplified and compact construction than the bending machines heretofore proposed and in which the bending operation is carried out by moving a bending die upwardly and around an anvil die so that either individual or successive bends can be readily made in the work material and such that the material being bent swings upwardly to an out-of-the-way position.

A further object of this invention is to provide an improved bending machine of this character, having a novel relative arrangement for the anvil die and bending die such as to enable work material to be readily fed to the machine from a convenient working position at the front thereof and which will readily accommodate work material of any width or length within the capacity of the machine.

Still another object of this invention is to provide an improved machine of this kind, having novel means for mounting and actuating the movable anvil and bending dies so as to effectively accomplish the desired work clamping and bending operations.

Yet another object of the present invention is to provide an improved bending machine of the character mentioned, which is readily adaptable for carrying out the bending operation so that the relative rocking between the bending and anvil dies will be accomplished either as a wiping action or as a rolling action without relative slippage, depending upon the characteristics and requirements of the work material.

The invention can be further briefly summarized as consisting in certain novel combinations and arrangements of parts hereinafter described and particularly set out in the appended claims.

In the accompanying sheets of drawings:

Fig. 1 is a side elevation showing one form of bending machine embodying the construction of the present invention.

Fig. 2 is a partial side elevation similar to Fig. 55

2

1 and showing the work material with only one bend formed therein.

Fig. 3 is another side elevation similar to Fig. 1 but showing the work material with two bends formed therein.

Fig. 4 is a front elevation of the machine showing the same on a larger scale.

Fig. 5 is a longitudinal sectional view taken through the machine on line 5—5 of Fig. 4.

Fig. 6 is a partial plan view of the machine.

Fig. 7 is a perspective view showing the cylinder and linkage for actuating the anvil die for clamping or releasing the work material.

Fig. 8 is a partial vertical sectional view taken substantially on line 8—8 of Fig. 4.

Fig. 9 is a partial vertical sectional view taken on line 9—9 of Fig. 6.

Fig. 10 is another partial vertical sectional view taken substantially on line 10—10 of Fig. 5.

Fig. 11 is a partial longitudinal sectional view taken through a modified form of the improved bending machine.

Fig. 12 is a similar partial longitudinal sectional view taken through another modified form of the improved bending machine.

Fig. 13 is a partial transverse section view taken through the modified bending machine of Fig. 12, the view being taken substantially on line 13—13 of Fig. 12.

Fig. 14 is another partial longitudinal sectional view thereof taken on line 14—14 of Fig. 13.

Fig. 15 is a transverse sectional view of the work material being bent in Figs. 11 and 12.

Proceeding now with a more detailed description

35 of the present invention, I will describe first the machine or embodiment which is illustrated in Figs. 1 to 10 inclusive and wherein the work material being bent is shown in this instance as being in the form of pipes or tubes 10a, 10b, and 10c of different diameters. This machine

40 comprises in general an upright frame 11 provided with cooperating die members and with a hollow structure or wing which is pivoted on the frame for swinging movement. The cooperating die members include a stationary die member or

45 work support 13, an anvil die 14 which is movable toward and away from the member 13 for clamping or releasing the work material, and a bending die 15 which is actuated by the wing 12 for rocking cooperation with the anvil die.

The frame 11 comprises an upright hollow structure having laterally spaced substantially parallel side walls 16 and 17 which are connected adjacent the bottom of the frame by means of a substantially horizontal floor portion

18 and are also connected adjacent the front of the frame by a laterally extending upright wall 19. The wall 19 extends for only a portion of the height of the machine, as shown in Fig. 5, and at its upper edge is provided with a laterally elongated ledge or overhang 20 which forms a table portion or mount for the die member or work support 13. Rearwardly or inwardly of the table portion 20 the frame 11 is also provided with a laterally elongated substantially horizontal table portion 21 which extends between the side walls 16 and 17. The table portion 21 is formed of metal plate which is suitably supported at the front of the machine either on the table portion 20 or on the die member 13 and at the rear of the machine by the crossbar 21a. Suitable stops or gauges 22 and 23 are provided on the table portion 21 for cooperation with the inner end or ends of the work material when the latter is inserted into the machine from a working position in front thereof. Additional transverse work supports 24 can be provided at appropriate heights above the table portion 21 if needed or desired. The table portion 21 and the spaced uprights forming the side walls 16 and 17 define a compartment in the lower portion of the frame which houses certain pressure fluid apparatus described hereinafter.

The anvil die 14 is supported and actuated by a movable carrier 25 which is here shown as being a substantially U-shaped member having a transverse front portion 25a to which the anvil die is bolted or otherwise suitably connected and a pair of laterally spaced rearwardly extending arms 25b which lie just inwardly of the side walls 16 and 17 and are pivotally connected with the latter by means of the pivot pins 26. Pairs of cooperating guide elements 27 and 28 are provided on the carrier 25 and the side walls of the frame 11 for confining and guiding the carrier during its swinging movement in the frame. With the carrier 25 mounted in the frame 11 as just described, it will be seen that lowering and lifting of this carrier will cause the anvil die 14 to be moved toward or away from the work supporting die 13 so as to cooperate therewith for clamping or releasing the work material.

The carrier 25 can be actuated by any suitable power means and in this instance I show a double acting fluid pressure cylinder 30 for this purpose. The cylinder 30 is preferably a hydraulic cylinder having connections 31 and 32 at the upper and lower ends thereof for supplying or exhausting the actuating liquid which is preferably a suitable oil. The cylinder 30 has a reciprocable piston therein from which a piston rod 33 extends through the upper end of the cylinder and is attached to a lever 34, the latter being keyed or otherwise connected to a transverse rock shaft 35. A pair of levers 36 spaced axially of the rock shaft 35 and keyed thereto are connected with the arms 25b of the carrier 25 as by means of the links 37. The lower end of the cylinder 30 is anchored on the floor portion 18 of the frame as by means of the pivotal connection 38 which permits swinging of the cylinder during the rocking of the shaft 35.

A supply of liquid for actuation of the cylinder 30 is contained in a reservoir or tank 39 which is also supported on the floor portion 18 of the frame 11. Liquid from the tank 39 is supplied to the cylinder 30 by a suitable pump 40 which is driven from an electric motor 41 by means of the belt 42. The electric motor 41 may likewise be supported on the floor portion 18 of the frame.

In the arrangement just described it will be seen that the cylinder 30, the tank 39, and the electric motor 41 which are supported on the floor portion 18 are all housed in the hollow frame 11.

The wing 12 which actuates the bending die 15 comprises a laterally elongated generally flat plate-like hollow structure or body which extends across the front of the machine and is provided adjacent its ends with a pair of supporting arms 44. The arms 44 are provided with suitable bearings at their outer ends by which the wing is pivotally mounted on a pair of substantially aligned pivot pins 46 which project laterally outwardly in opposite directions from the sides 16 and 17 of the frame 11. The pivot pins 46 are disposed substantially coaxially of the laterally elongated anvil die 14 so that the wing 12 can be swung forwardly and upwardly around the anvil die as will be explained more fully hereinafter. The hollow body of the wing is defined by integrally connected side and end walls 12a and 12b, the latter of which have openings 12c therein.

As shown in the drawings, the wing 12 also includes a die carrier in the form of a plate 50 which is located between the spaced arms 44 and extends in a direction substantially normal to the general plane of the hollow body of the wing. The plate 50 is elongated laterally of the machine and forms a carrier for the bending die 15, this die being bolted or otherwise suitably attached to the plate on the upper side thereof. The plate 50 is provided at the ends thereof with a pair of spaced arms or yokes 51 which have pivot recesses 52 in their upper or outer ends and which recesses are rockable on pivot pins 53 which extend inwardly from the side walls 16 and 17 of the frame 11 in substantially coaxial alignment with the previously mentioned pivot pins 46 of the wing 12. The yoke recesses 52 and the pivot pins 53 constitute cooperating fulcrum elements by which the plate 50 is mounted for swinging movement on the frame 11 while being carried by the wing 12. As shown in Fig. 9 the oppositely extending pivot pins 46 and 53a are carried by an adaptor body 17a which extends through an opening of the side wall 17 and is bolted thereagainst.

The wing 12 also includes a pressure roller 54 and a pair of laterally spaced supporting rollers 55 located outwardly of, or to the front of, the pressure roller. The pressure roller 54 is shiftably mounted in the hollow body of the wing with its opposite ends extending outwardly through the openings 12c and is held in engagement with the underside of the plate 50 by means of the compression springs 56. These springs act to urge the bending die 15 toward the anvil die 14 for applying pressure to the work material during the bending operation and also act to yieldably hold the above mentioned cooperating fulcrum elements 52 and 53 in engagement with each other. The springs 56 are disposed in the end openings 12c of the wing so as to extend between the spring seats 56a and the shiftable bearings 54a of the roller 54. The compression of the springs 56 can be varied or adjusted by means of the screws 57 engaging the spring seats 56a. The rollers 55 support the forwardly extending or overhanging portion of the plate 50 and effectively prevent any excessive relative rocking or tilting of the plate.

Relative slipping between the surface of the pressure roller 54 and the underside of the plate 50 is prevented by providing the roller with axially spaced pinions or annular groups of teeth 58 which mesh with racks 59 provided on the under-

side of the plate adjacent the ends thereof. The inner rear longitudinal edge of the plate 50 carries a projection or flange 60, preferably beveled, which engages under a lip or flange 61 provided on the table portion 20 of the frame for assisting in supporting the plate when the wing 12 is in its lower position corresponding with the initial position of the bending die 15. The lip 61 will insure accurate alignment of the supporting and bending dies 13 and 15 and will act as a stop for taking the thrust of the pressure roller 54 while the wing is in its lower position and while the work material is being inserted into the machine from the front thereof.

The wing 12 is actuated by power means preferably in the form of a pair of hydraulic cylinders 63 located just outwardly of the upright side walls 16 and 17 of the frame 11. The cylinders 63 have suitable connections 64 and 65 adjacent their ends for supplying and exhausting the motive fluid. These cylinders are disposed in relatively inclined relation so that their thrust can be applied to the wing in a direct and effective manner and have their inner or rear ends anchored on the frame 11 as by means of the pivotal connection 66. The cylinders 63 have reciprocable pistons therein attached to piston rods 67 which project from the front or outer ends of these cylinders and are pivotally connected to the spaced lugs 68 of the wing 12 by means of the pivot pins 69. When pressure fluid is supplied to the inner ends of the cylinders 63 the wing 12 is swung outwardly and upwardly on the pivot pins 46 to or toward the broken line position shown in Fig. 5, thereby causing the bending die 15 to travel around the anvil die 14. When pressure fluid is supplied to the outer ends of the cylinders 63 the wing 12 is returned or lowered to its full line initial position shown in Figs. 4 and 5.

The pressure fluid for actuating the cylinders 63 is supplied thereto by the above mentioned pump 40 and is controlled by suitable valve means (not shown) adapted to be actuated by a control lever 70. A similar lever 71 is provided for actuating suitable valve means (not shown) for controlling the supply of pressure fluid to the cylinder 30 which causes opening and closing of the anvil die 14. The levers 70 and 71 can be located on the side wall 16 of the frame 11 at a conveniently accessible point as shown in Fig. 1. A suitable electric switch 72 is also located on the frame adjacent the levers 70 and 71 and controls the operation of the electric motor 41.

The cooperating die members 13, 14, and 15 will be described next. The stationary die member 13 forms a work support, as mentioned above, against which the work material is clamped by the movable anvil die 14. Each of the die members 13, 14, and 15 may comprise a single laterally elongated body having a surface shape or contour appropriate for the particular work material being handled and the particular forming or bending operations being carried out thereon. In the machine illustrated in Figs. 1 to 10 inclusive, in which the work material is in the form of pipes 10a, 10b, and 10c of three different diameters, each of the die members 13, 14, and 15 comprises three sections which extend laterally of the machine in substantial alignment.

The sections of the stationary die member 13 are designated 13a, 13b, and 13c, all of which are bolted or otherwise attached to the table portion 20 of the frame 11. The anvil die 14 comprises corresponding sections 14a, 14b, and 14c, which are bolted to the transverse portion 25a of the die

carrier 25. The bending die 15 comprises corresponding sections 15a, 15b, and 15c, which are bolted or otherwise attached to the plate 50 of the wing 12.

The anvil die 14 is constructed of a shape to provide a rounded forward portion 75 (see Fig. 5) around which the work material is to be bent, and a rearwardly extending substantially straight portion 76 which cooperates with the stationary die member 13 for clamping the work material against the latter. The stationary die member 13 and the bending die 15 are both plate-like structures which are straight, as distinguished from the curved portion 75 of the anvil die 14. When the cooperating die members 13, 14, and 15 are intended for use in bending pipe, as shown in this instance, they are provided with grooves or recesses having a transverse curvature corresponding substantially with the outside diameter of the pipe to be received therein. The grooves 77 of this character which are provided in the anvil die 14 extend continuously around the curved portion 75 and along the rearwardly extending straight portion 76. The corresponding grooves 78 and 79 of the die members 13 and 15 extend across the latter die members from the front to the back thereof, with the grooves 79 of the die member 15 in substantial alignment with the groove 78 of the die member 13. The grooves 78 and 79 of the die members 13 and 15 are complementary to the grooves 77 of the anvil die 14, so that approximately one-half of the pipe to be bent is contained in the grooves of the die members 13 and 15, and the other half of the pipe is contained in the groove 77 of the anvil die 14.

When the pipes are to be placed in the machine, the cylinder 30 is actuated to lift the carrier 25, thereby opening the anvil die 14 relative to the work supporting die 13 so that the pipes can be inserted endwise into the aligned grooves of the die members 13 and 15. When the desired number of pipes have been inserted into the machine, the cylinder 30 is actuated to lower the anvil die 14, thereby clamping the pipes against the stationary die member 13. The machine is now loaded and ready for the bending operation, which is carried out by actuating the cylinders 63 so as to swing the wing 12 upwardly to or toward its broken line position shown in Fig. 5. During this swinging of the wing 12 the bending die 15 travels around the curved portion of the anvil die 14 and bends the pipes against the curved portion of the latter so that they assume a corresponding curvature. The bending operation can be accomplished by one or more such strokes of the wing 12 as may be needed, after which the wing is returned to its initial position in which it is shown in full lines in Figs. 4 and 5.

The curvature or shape to which the pipes or other work material is to be bent is determined by the shape or curvature of the rounded forward portion of the anvil die 14. By substituting different anvil dies of appropriate curvature in the machine, the work material can be bent to any desired shape or radius of curvature. In the drawings I show the sections 14a, 14b and 14c of the anvil die 14 provided with different radii of curvature and which radii decrease with the size of the pipes to be bent. In other words, the die section 14a which handles the large size pipe 10a has the largest radius of curvature, and the die section 14c which handles the smallest size pipe 10c has the smallest radius of curvature. The intermediate die section 14b which handles the

intermediate size of pipe 10b has an intermediate radius of curvature.

The thickness of the die members 13 and 15 depends upon the radius of curvature of the anvil die 14, and the thickness of the different sections of the die members 13 and 15 varies (see Figs. 4 and 10) with the variation in the curvature of the different sections of the anvil die. In other words, the sections 13a and 15a which cooperate with the section 14a of the anvil die are of minimum thickness, and the sections 13c and 15c which cooperate with the section 14c of the anvil die, are of maximum thickness. The intermediate sections 13b and 15b which cooperate with the intermediate section 14b of the anvil die are of an intermediate thickness.

In carrying out the bending operation in the form of the machine illustrated in Figs. 1 to 10 inclusive, in which the plate 50 of the wing 12 is fulcrumed on the frame 11 by means of the pivot recesses 53 of the yokes or arms 52, the movement of the bending die 15 around the anvil die 14 takes place with a wiping action. Likewise, in this form of the machine the plate 50 does not travel through or transversely of the wing 12 during the swinging of the latter, but remains substantially locked in position in the wing with the pressure roller 54 acting on the under side of the plate so as to apply its pressure substantially on a radial line which passes through the common pivot axis about which the wing 12 and the plate 50 are swung. The combined swinging movement of the wing 12 and the pressure of the roller 54 cause the bending die 15 to bend the work material smoothly to the desired shape or radius substantially without the formation of any irregularities or wrinkles in the work material.

Figs. 1, 2 and 3 illustrates the above described operation of the machine in a somewhat diagrammatic manner. Fig. 1 shows the pipes 10a, 10b and 10c as having been inserted into the machine, and shows the wing 12 ready to begin its upward swing for the bending operation. Fig. 2 shows the machine at the completion of the first bending operation, at which time the wing 12 is in an elevated forwardly extending position, and the bent portions of the pipes 10a, 10b and 10c extend upwardly above the machine in an out-of-the-way position. Fig. 3 shows the machine at the completion of a second bending operation which has been performed upon the same groups of pipes 10a, 10b and 10c. In this improved machine it will be seen that when a second bend is formed in the work material the previously bent portion is deflected or swung toward the rear of the machine, so that a minimum amount of floor space is needed to accommodate this machine and the bending operations performed thereby.

Instead of using the machine for bending groups of pipes as above explained, it can also be used for bending metal sheets or the like to any desired radius of curvature, or to a relatively sharp angular bend as shown in Fig. 11. When the machine is used to operate on metal sheets or plates for this purpose, it will be understood of course that the above described complementary grooves are omitted from the cooperating die members and the working surfaces of these die members will be smooth or flat.

Fig. 11 shows a modified bending machine which is substantially identical with that illustrated in Figs. 1 to 10 inclusive, with the exception of the die members, which in this view are shown as being provided with the above mentioned smooth or flat working faces for performing

the bending operations on the metal sheet or plate 81. In Fig. 11 the anvil die 82 has a relatively sharp front edge 83, around which the plate 81 is bent and a substantially flat lower face 84 for clamping cooperation with the flat upper face 85 of the stationary die member 86. The bending die 87 is carried by a plate 88 of the wing 89, and has a substantially flat working surface 90 which travels or swings around the anvil die 82 during the swinging of the wing.

In Figs. 12, 13 and 14 I show another modified form of the above described bending apparatus. In this modified construction the bending machine is substantially identical with the machine illustrated in Figs. 1 to 10 inclusive, with the exception of the cooperating die members and the manner in which the plate 92 of the wing 93 is fulcrumed on the frame of the machine. The dies embodied in this modified form of bending machine include an anvil die 94, a stationary work supporting die 95 and a bending die 96. The anvil die 94 has a rounded forward portion 97 which may be of any desired radius of curvature and around which the metal sheet 98 is bent. The anvil die 94 also has a substantially flat lower face 99 for clamping cooperation with the flat upper face 100 of the die member 95. The bending die 96 has a substantially flat inner side face 101 which comes into substantially meeting relation with a corresponding face on the die member 95 when the wing 93 is in its initial or lower position, and a substantially flat upper working face 102 which travels around the curved surface 97 of the anvil die 94 during the bending operation.

In operating on certain kinds of work such as the metal sheet 98 shown in this instance, it is desirable that the bending die 96 travel around the anvil die 94 with a true rocking motion substantially without any relative slippage therebetween. To accomplish this the arms or yokes 104 located at the ends of the plate 92 are provided with racks 105 which mesh with gear sectors 106 provided on the frame of the machine. The racks 105 and the gear sectors 106 with which they cooperate, constitute fulcrum elements which are maintained in cooperating relation by the pressure of the springs 107 of the wing 93, so as to form a fulcrum which permits swinging or rocking of the plate 92 around the anvil die 94 on substantially the same pivot axis as the wing 93 during the bending operation.

When the bending operation is carried out in this modified form of machine shown in Figs. 12 to 14 inclusive, the plate 92 which carries the bending die 96 has some relative movement through or transversely of the wing 93 as the latter is swung upwardly about its pivot axis. This relative movement of the plate 92 accompanies the rocking movement around the anvil die 94 which is compelled by the meshing engagement of the racks and sectors 105 and 106 and takes place substantially in the plate's own plane and substantially normal to the body of the wing 93. During this movement of the plate 92 relative to the wing 93, the point of engagement of the pressure roller 108 travels along the underside of the plate but relative slippage between the pressure roll and plate is prevented by the teeth 109 of the roll engaging in the racks 110 of the plate. If the metal sheet 98 being bent has edge flanges 111 thereon, as shown in Figs. 12, 13 and 15, the bending die 96 is provided with angular or upstanding flange portions 112 at the ends thereof, which cooperate with end faces of the anvil die

94 for ironing the flanges 111 and holding the same from wrinkling during the bending operation.

When the bending operation is to be carried out with the above described true rocking action of the bending die relative to the anvil die, the machine is used in the form shown in Figs. 12, 13 and 14 in which the plate 92 of the wing has the above mentioned racks 105 on the arms or yokes thereof and the frame is provided with gear sectors 106 with which such racks cooperate. The bending machine shown in Figs. 1 to 10 inclusive, which performs the bending operation with a wiping action, can be readily adapted or converted to the rocking type of machine by merely substituting therein a plate of the character shown in Figs. 12, 13, and 14, in which the arms or yokes 104 are provided with the racks 105 and by substituting the adapter fittings 115 in the frame openings 116 in place of the fittings 11a shown in Fig. 9. As shown in Figs. 13 and 14, the adapter fittings 115 have outwardly projecting pivot pins 117 thereon, corresponding with the pivot pins 46 of Fig. 4, and on which the arms of the wing 93 are pivotally mounted. The gear sectors 106 are bolted or otherwise attached to the plate portions 118 of the adapters 115, with the centers of the gear sectors lying substantially on the common pivot axis of the pins 117 and the curved portion 97 of the bending die 94. This conversion can also be accomplished by merely detaching the yokes 51 from the plate 50 and substituting the yokes 104 of Fig. 14, and replacing the plain pivot pins 53 of Fig. 9 with the gear sectors 106 of Fig. 14.

From the foregoing description and the accompanying drawings it will now be readily understood that the present invention provides an improved construction for bending machines, such that these machines can be simpler and more compact than has heretofore been the case, and the improved machine is capable of carrying out bending operations in a rapid and satisfactory manner on various kinds of work material including sheets, pipes, tubes and the like. It will be seen also that the improved construction provides a machine which will accommodate, or can be easily adapted to, various widths and lengths of work material and that such material can be readily inserted into or removed from the machine from a convenient working position at the front thereof.

While I have illustrated and described my improved bending apparatus in considerable detail, it will be understood of course that I do not wish to be correspondingly limited but regard my invention as including all changes and modifications coming within the spirit of the invention and the scope of the claims hereof.

Having thus described my invention, I claim:

1. In a bending machine, a frame having laterally spaced uprights and a substantially horizontally elongated work support between said uprights, substantially horizontally elongated anvil die means above said work support and substantially coextensive therewith, means mounting said anvil die means on said frame for movement toward and away from said work support for clamping work material therebetween, a substantially horizontally elongated structure mounted on said frame so as to swing upwardly around said anvil die means, substantially horizontally elongated bending die means carried by said structure and cooperating with said anvil

die means for bending a portion of said material upwardly around the latter during the swinging of said structure, the mounting means for said anvil die means comprising elongated members lying adjacent said uprights and pivoted thereon at a point remote from said work support, a laterally extending rock shaft journaled in said uprights, a power cylinder located between said uprights and operably connected with said shaft to rock the same, levers connected with said rock shaft adjacent said uprights and extending in a direction away from the pivots for said elongated members, and links pivotally connected with said levers and said elongated members for actuating the latter from said rock shaft.

2. In bending apparatus, a frame, elongated anvil die means on said frame, means substantially coextensive with said anvil die means and cooperating therewith for clamping work material therebetween, an elongated structure having pivotal connection with said frame at points outwardly of the ends of said anvil die means so as to swing around said anvil die means on an axis substantially coextensive therewith, means for swinging said structure, an elongated plate separate from but carried and actuated by said structure and having spaced arms fulcrumed on said frame for movement of said plate with said structure and substantially about the pivot axis of the latter, bending die means carried by said plate and cooperating with said anvil die means for bending the work material around the latter during the swinging of said structure, a roller carried by said structure and engaging said plate, spring means acting on said roller for urging said bending die means toward said anvil die means, and cooperating gear teeth in meshing engagement on said roller and plate.

3. In bending apparatus, a frame, an elongated work support on said frame, elongated anvil die means substantially coextensive with said work support and movable toward the latter for clamping work material therebetween, an elongated structure having spaced pivotal connections with said frame at points adjacent the ends of said anvil die means so as to swing around the latter on an axis substantially coextensive therewith, means for swinging said structure, a plate carried by said structure and extending substantially normal thereto, said plate being supported by said structure so as to be capable of relative movement substantially in its own plane and transversely of said structure, gear sectors on said frame adjacent said pivotal connections, spaced arms projecting from one side of said plate and having racks thereon which mesh with said gear sectors, bending die means on said one side of said plate and cooperating with said anvil die means for bending the work material around the latter during the swinging of said structure, racks on the other side of said plate, a roller engaging said other side of the plate and having gear teeth thereon which mesh with the last mentioned racks, and resilient pressure means acting through said roller for urging said bending die means toward said anvil die means.

4. In a bending machine, a frame having laterally spaced uprights forming the sides of the frame and a horizontally elongated work support extending between said uprights at the front of the frame, said uprights being of a width such that said frame has a substantial depth and being of a height to extend above the plane of said

11

work support at the front and rear portions of the frame, a carrier located above said work support and between said uprights and having rearwardly extending arms pivoted on said uprights adjacent the rear of the frame, a horizontally elongated anvil die mounted on said carrier for cooperation with said work support in clamping work material thereagainst, a horizontally elongated wing pivotally mounted on said frame adjacent the front thereof so as to swing forwardly and upwardly around said anvil die, a horizontally elongated bending die carried by said wing and adapted to cooperate with said anvil die for bending said work material upwardly around the latter, means for imparting such forward and upward swinging movement to said wing, a laterally extending rock shaft journalled in said uprights and having levers mounted thereon adjacent said uprights, a power cylinder operably connected with said rock shaft to rock the same, and links pivotally connecting said levers with said arms for actuating said carrier from said rock shaft.

5. In a bending machine, a frame having laterally spaced uprights forming the sides of the frame and a horizontally elongated work support extending between said uprights at the front of the frame, said uprights being of a width such that said frame has a substantial depth and being of a height to extend above the plane of said work support at the front and rear portions of the frame, a carrier located above said work support and between said uprights and having rearwardly extending arms lying adjacent the inner sides of the uprights and pivoted on said uprights adjacent the rear of the frame, a horizontally elongated anvil die mounted on said carrier for cooperating with said work support in clamping work material thereagainst, a horizontally elongated wing having horizontally spaced arms pivotally mounted on said frame adjacent the front thereof and on the outer sides of said uprights so as to swing forwardly and upwardly around said anvil die, a horizontally elongated bending die carried by said wing and adapted to cooperate with said anvil die for bending said work material upwardly around the latter, means for imparting such forward and upward swinging movement to said wing comprising a pair of pressure fluid responsive cylinders pivotally mounted on said uprights on the outside thereof and operably connected with said wing at corresponding horizontally spaced points, a laterally extending rock shaft journalled in said uprights and having levers mounted thereon adjacent said uprights, a power cylinder operably connected with said rock shaft to rock the same, and links pivotally connecting said levers with said arms for actuating said carrier from said rock shaft.

6. In bending apparatus, a frame, laterally elongated anvil die means on said frame, laterally elongated work engaging die means on said frame substantially coextensive with said anvil die means and cooperating therewith for clamping work material therebetween, a laterally elongated generally flat structure having laterally spaced arms pivotally connected with said frame at points outwardly of the ends of said anvil die means so as to swing forwardly and upwardly around said anvil die means on a pivot axis substantially coextensive therewith, means for swinging said structure, a laterally elongated plate separate from but carried and actuated by said structure by being supported thereon between the arms

12

thereof and extending substantially normal to the plane of said structure, said plate having arms projecting from one side thereof and adjacent its ends and fulcrumed on said frame for arcuate movement of said plate around said anvil die means with said structure and substantially about the pivot axis of the latter, bending die means carried by said plate and cooperating with said anvil die means for bending the work material around the latter during the swinging of said structure, and resiliently acting pressure means carried by said structure and acting continuously on said plate for urging said bending die means toward said anvil die means.

7. In bending apparatus, a frame having at the front thereof a laterally elongated work supporting portion including a laterally elongated forwardly overhanging lip, a laterally elongated work supporting die on said work supporting portion, laterally elongated anvil die means above said work supporting die, a movable carrier for said anvil die means and mounting the latter for movement toward said work supporting die for clamping work material against the latter, a structure elongated in the direction of said anvil die means and having spaced arms pivotally connected with said frame outwardly of the ends of said anvil die means so as to mount said structure on said frame for swinging from an initial depending position in a direction forwardly and upwardly around said anvil die means, means for swinging said structure, roller means carried by said structure, a plate disposed between said spaced arms and extending substantially normal to the plane of said structure and supported by said roller means with a forwardly extending portion of the plate overhanging said roller means, cooperating means on said frame and plate for fulcruming the latter on said frame during the swinging of said structure, laterally elongated bending die means carried by said plate and cooperating with said anvil die means for bending the work material around the latter during said swinging of said structure, pressure means acting against said plate through said roller means for urging the bending die means toward said anvil die means, and a laterally elongated rearwardly projecting ledge on said plate and engageable under said overhanging lip when said structure is in said initial position for assisting in supporting the overhanging portion of said plate.

8. In bending apparatus, a frame, a laterally elongated work supporting die on said frame at the front thereof, laterally elongated anvil die means above said work supporting die, a movable carrier for said anvil die means and mounting the latter for movement toward said work supporting die for clamping work material against the latter, a laterally elongated structure having laterally spaced arms pivoted on said frame for swinging of said structure forwardly and upwardly around said anvil die means on an axis substantially coextensive with the latter, means for swinging said structure, a laterally elongated plate separate from but carried and actuated by said structure by being supported thereon between the arms thereof and adjacent its ends, gear sectors on said frame adjacent the ends of said anvil die means, racks on the arms of said plate and having meshing engagement with said gear sectors so as to permit movement of said plate substantially in its own plane and relative to said struc-

13

ture during the swinging of said structure, bending die means carried by said plate on said one side thereof and having rocking cooperation with said anvil die means for bending the work material around the latter during the swinging of said structure, and resiliently acting pressure means carried by said structure and acting on the opposite side of said plate.

9. In bending apparatus, a frame having laterally spaced uprights, a laterally elongated work supporting die on said frame at the front thereof, laterally elongated anvil die means above said work supporting die, a movable carrier for said anvil die means and mounting the latter for movement toward said work supporting die for clamping work material against the latter, a laterally elongated structure having laterally spaced arms pivoted on said frame on the outside of said uprights for swinging of said structure forwardly and upwardly around said anvil die means, means for swinging said structure, a laterally elongated plate separate from but carried and actuated by said structure by being supported thereon between the arms thereof and extending substantially normal to the plane of said structure, said plate having arms projecting from one side thereof and adjacent its ends, gear sectors on said frame adjacent the ends of said anvil die means and located on the inside of said uprights, racks on the arms of said plate and having meshing engagement with said gear sectors so as to permit movement of said plate substantially in its own plane and relative to said structure during the swinging of said structure, bending die means carried by said plate on said one side thereof and having rocking cooperation with said anvil die means for bending the work material around the latter during the swinging of said structure, and resiliently acting pressure means carried by said structure and acting on the opposite side of said plate.

10. In bending apparatus, a frame having laterally spaced uprights, a laterally elongated work supporting die on said frame at the front thereof, laterally elongated anvil die means above said work supporting die, a movable carrier for said anvil die means and mounting the latter for movement toward said work supporting die for clamping work material against the
